UNITED STATES PATENT OFFICE.

ALFRED PICK, OF CLEVELAND, OHIO, ASSIGNOR, BY MESNE ASSIGNMENTS, TO THE VAN DORN ELECTRIC TOOL COMPANY, OF CLEVELAND, OHIO, A CORPORATION OF OHIO.

ELECTROMAGNETIC CIRCUIT-CLOSING AND CIRCUIT-BREAKING DEVICE.

1,146,734.

Specification of Letters Patent.

Patented July 13, 1915.

Application filed October 16, 1911. Serial No. 654,798.

To all whom it may concern:

Be it known that I, ALFRED PICK, a subject of the Emperor of Austria-Hungary, residing at Cleveland, in the county of 5 Cuyahoga and State of Ohio, have invented certain new and useful Improvements in Electromagnetic Circuit-Closing and Circuit-Breaking Devices, of which the following is a specification.

10 My invention relates to electromagnetic circuit closing and circuit breaking devices, and its object is to improve upon devices of this type and to provide simple and efficient apparatus which has decided advantages 15 over those now known in the art.

To these ends my invention resides in arrangements and construction of parts which I will describe in the following specification and the novel features which I will set forth 20 in the appended claims.

The device of my invention is designed to effect the electromagnetic control, usually from a distance, of any desired electric motor device, preferably by the control thereof, through the medium of a push-button 25 switch, provided upon the actuated appliance.

I will first briefly explain the general features of my improved device in connection 30 with Figure 1, by pointing out that it consists of an actuating coil A, a reciprocated contact-member B with suitable contact-brushes attached thereto, and an operating switch magnet C, having circuit-closing 35 parts, actuated by the plunger or movable core thereof. Below this, is positioned a cup D, containing multiple-contact members which form with the contacts upon said core or plunger, a multiple break-switch for the 40 main circuit, providing in the particular device herein described, for the opening of the circuit at six different points.

The entire device, preferably, is contained within a water-tight casing for the protection thereof, into which is led the electric cable.

These features with many additional details, will be explained in connection with the accompanying drawings, wherein.—

50 Fig. 1 is a vertical, sectional view of the device of my invention. Fig. 2 is a fragmentary, transverse, sectional view, showing the reciprocating contact-member

B taken on the line A—A of Fig. 1 viewing upwardly. Fig. 3 is a similar view, showing the co-acting contacts mounted upon their insulating block taken on the line B—B of Fig. 1, viewing downwardly. Fig. 4 is a transverse, sectional view, illustrating the stationary multiple-break-contacts taken 60 on the line C—C of Fig. 1, viewing upwardly. Fig. 5 is a similar view, showing their co-acting movable contacts taken on the line D—D of Fig. 1, viewing downwardly. Fig. 6 is an enlarged view, partly 65 in elevation and partly in vertical section, showing the upper, reciprocating contact-members and their co-acting parts.

Like characters of reference designate corresponding parts in all of the figures. 70

Referring to the first sheet of drawings, 1 designates a spool or bobbin of iron which in this case is not homogeneous but has a sleeve 3 of non-magnetic material welded in such a manner as to form part of the 75 spool.

2 designates strips exteriorly connecting the ends of the spool so as to form a closed magnetic circuit.

4 designates a plunger, movable inside of 80 spool 1, at the upper end of which is attached a rod 6. Said plunger has near its outer end a collar 15, forming an abutment or stop, when brought into engagement with the downward extremity of cup 44. Spring 85 16 presses against collar 15 and against the face of the spool 1, thus holding the plunger in its lower position.

Near the lower end of the plunger, is attached a multiple-contact arrangement holding contact-parts 52, which are built up of individual strips and securely attached to an insulating disk 53. 90

54 is an insulating spider separating the contact-parts 52. For the purpose of properly insulating said contacts, an insulating disk 55 separates the contact-parts from the plunger. A washer 56 and a nut 57 hold the contact-parts upon said plunger. 95

At 58 the lower end of the plunger projects into a sleeve, 58' formed within the casting 60, for the purpose of guiding the moving plunger. 100

I may term a floating magnet pole inside of the spool 1, having in one side an 105 annular slot 42 to receive a spring 43. On

the other side is provided a shoulder 72, forming with a similar shoulder within the spool 1, a limit stop.

5 20 is a stationary pole, securely attached to the spool 1, in a slot of which is placed a spring 33, being held in place by means of the screws 40 and 41. Said spring, as I will later fully explain, has as its object the locking and unlocking of the floating 10 detent member, as shown at 71. 7 is the exciting coil wound on spool 1, through which the controlled current is designed to flow.

15 At the other end of the device is provided a smaller iron spool 8, of which a brass sleeve 10 forms a part.

9 designates exterior iron bars, connecting the ends of the spool and having the same object previously explained.

20 12 is a stationary pole projecting toward the middle of the spool and securely attached to said spool by means of screws 13.

11 is a contact-making plunger, carrying contact-parts 74, held in position by means 25 of a screw member 30 between insulating parts 21 and 22.

30 An insulating block 18 below spool 8, mounts the contact-ring 19, attached to said insulating block which forms a contact stop for the first mentioned contact 74. A spring 17 is adapted to hold the plunger 11 in its lower position.

35 14 is a fine wire coil wound on spool 8. As I will later explain, this arrangement serves as an actuating relay for establishing contact to close the main circuit.

40 A floating member 29 mounts the contacts 34 and 26, the purpose of which I will later explain. Said member has terminal rods 71 and 75 projecting into openings bored in the parts 30 and 20 respectively, adapted to 45 guide the member 29 in its longitudinal movement. 35 is a rod attached to said member, the other end of which is adapted to slide in slot 36 to prevent the member 29 from rotating.

50 38 is an insulating body securely attached to 29, whereon contact 34 is secured by means of screw 37. 27 is an insulating disk, positioned beneath said contact.

28 is an insulating sleeve with collar adapted to insulate the contact-parts.

55 23 is an insulating block carrying contact-parts 24 and 25, which in turn are securely attached to spool 1.

60 26 is a bowed contact adapted to open and close the circuit between contacts 24 and 25. Said contact 26 is attached to member 29 with its insulating parts 27 and 28 by means of nut 31.

32 is a normally compressed spring adapted to open the contacts 24 and 25, when the locking spring 33 releases at 71.

65 As can be seen from the wiring diagram in conjunction with Fig. 1, the fine wire coil

14 has terminals that independently lead to a push-button P, whereas the power-leads to coil and switch and contact-points are separate, and are to be connected in series with the machine or machines, whose current is to be controlled by this device, and which-power-leads in practice may be joined in such a manner as to form a unit cable which may be brought out through the opening 62, provided with suitable packing 68, a washer 69 and a screw 70, by which arrangement the cable may be brought out and still maintain the device water-tight within its protective casing.

70 The wiring diagram shown in connection with Fig. 1, will now be used to explain the operations of my relay-actuated circuit-closing device, which serves also as an automatic maximum cut-out. This circuit-closing switch and automatic cut-out may be 80 used for various purposes in the art. The one disclosed has for its purpose the control of the operating current by means of a push-button, provided on portable electric tools as well as providing efficient means 85 for opening the circuit when the tool reaches a certain overload.

90 When the push-button P is closed, current will flow from battery B' or other source of current, over conductors a b and through the windings 14, thus energizing the magnetic circuit and causing the plunger 11 to move upwardly, thereby compressing the spring 17 and at the same time making contact between 19 and 74 and opening the 95 shunt circuit between 74 and 34. Thus the main circuit is closed, and current will flow through the coil 7. Circuit may be traced from the lower pole of battery B', conductor c, through coil 7, conductor d, closed-contacts 74, 19, conductor e, closed-contacts 25, 26, conductor f, through the motor m to the opposite pole of the battery or other source of current. The magnetic circuit thus energized by this coil, will cause the plunger 4 100 to move inwardly, until engagement is effected between the contacts 45 and 52.

105 When the push-button is released, the spring 17 pushes the plunger 11, outwardly opening the circuit between 19 and 74 and making contact between 34 and 74 and thereby short circuiting the coil 7. Very little current will go through the coil, the magnetic lines of that circuit will disappear and the spring 16 will drive the plunger 4 110 outwardly and open the electric circuit. If, however, there should be an overload, mean-time, the plunger 4, together with the floating pole 5 will move far enough as to cause the rod 6 to strike the spring 33 so it will 115 release the floating member 29 at 71. Spring 32 will move the floating contact-member 29 upward, and contact between 24 and 26 will be opened, and contact will be established between 74 and 34. This will cause a short 120 125

circuiting of the coil 7. For this reason, the lines of force of that circuit will disappear, and the plunger will be thrown outwardly by which the circuit will be broken.

- 5 In order to start the operation again, the push-button P must be released, and spring 17 by throwing the plunger 11 outwardly, will push the member 29 into its initial position and will be held there and locked by 10 spring 33, and in order to place the machine again in operation, the push-button P must be closed. It will be noted that the circuit is broken only at the multiple-break switch, which in turn is controlled by aforesaid contacts 15 short circuiting the operating coil.

The arrangement of parts herein above described, affords an extremely compact device and saves considerable space and weight.

- 20 I have now explained the methods and principles of operating this device, and have set forth its general purpose.

Some of the features herein described, may be applied to various types of switches 25 and electric-current controlling-devices.

Having now described in detail the preferred embodiment of my invention, I claim as new, and desire to secure by Letters-Patent, the following:

- 30 1. In a device of the class described, the combination with two associated electro-magnets, of switch-contacts controllable by one of said electro-magnets, to close the circuit through the other magnet, a resiliently 35 actuated short-circuiting device provided for short-circuiting the electro-magnet controlling said switch contacts, a trip-mechanism normally restraining the same, and means whereby said trip mechanism is adapted for 40 actuation by the second electro-magnet, substantially as set forth.

2. In a device of the class described, the combination with an inclosing casing of an armature, an electro-magnet for controlling said armature, a relay device for controlling said electro-magnet, a secondary electro-magnetic switching-device adapted to actuate said relay device, multiple-break contacts for said electro-magnetic switching

device and controllable thereby, trip-mechanism also controllable thereby, and shunting contacts for the relay and means adapted to close said relay-shunting contacts by the actuation of the trip, substantially as set forth.

50 55

3. In a device of the class described, the combination with an electro-magnetic relay and its manually controlled circuit, of a secondary electro-magnetic switch associated therewith, and provided with a winding 60 in series relation with the controlled circuit, multiple-break contacts also positioned in said circuit, adapted to be maintained closed during the energization of said winding, trip-mechanism, means whereby said trip-mechanism is adapted to be actuated upon the abnormal energization of said winding and contacts controlled thereby, for effecting the opening of the controlled circuit, substantially as set forth.

65 70

4. In a device of the class described, the combination with an inclosing casing of an electro-magnetic relay therein, a secondary electro-magnetic switch associated therewith, for controlling the power circuit, its 75 windings being in series relation with said circuit, a composite core-member controlled by the latter, multiple-break contacts thereon, governing the power-circuit, overload switch-contacts for said secondary electro-magnetic switch and means for actuating the same upon the abnormal energization of the series windings including a float member, a resilient releasing member for the latter, a second resilient member for automatically 80 actuating said float-member, said float-member being adapted to coöperate with said composite core and said break-contacts to cause said overload contacts to effect the 85 opening of the circuit, substantially as set forth.

90

In testimony whereof I do now affix my signature in the presence of two witnesses this 29th day of September, 1911.

ALFRED PICK. [L.S.]
